STEEL HEDDLE FRAME

Howard O. Coddington, Spartanburg, S. C., assignor to The Andrews Company, Spartanburg, S. C.

Application December 2, 1933, Serial No. 700,745

5 Claims. (Cl. 139—92)

This invention relates to steel heddle frames, the primary object of the invention being to provide a heddle frame designed especially for use with sectional heddles.

5 An important object of the invention is to provide a steel heddle frame including adjustable heddle bar supports which may be moved longitudinally of the heddle bars of the frame, to the end that the heddle sections may be uniformly 10 positioned throughout the length of the heddle frame.

A further object of the invention is the provision of means whereby the adjustment of the heddle bar supports may be readily and easily 15 accomplished without the necessity of removing the heddle bars thereon.

With the foregoing and other objects in view, which will appear as the description proceeds, the invention resides in the combination and arrangements of parts and in the details of construction hereinafter described and claimed, it being understood that changes in the precise embodiment of the invention herein disclosed, may 20 be made within the scope of what is claimed, 25 without departing from the spirit of the invention.

Referring to the drawings:

Figure 1 is an elevational view of a heddle frame, constructed in accordance with the invention.

Figure 2 is an enlarged sectional view taken on line 2—2 of Figure 1.

Figure 3 is an end elevational view of the heddle frame.

35 Figure 4 is a sectional view taken on line 4—4 of Figure 1.

Figure 5 is an enlarged detail view illustrating the means for securing the heddle bar to the heddle bar supporting rods, parts thereof being 40 shown in section.

Figure 6 is a side elevational view of the heddle bar supporting rod securing means, parts of the frame being shown in section.

Figure 7 is a transverse sectional view through 45 a heddle supporting rod.

Figure 8 is a fragmental sectional view illustrating the manner of securing the end bars to the upper and lower bars of the heddle frame.

Referring to the drawings in detail, the steel 50 heddle frame forming the subject matter of this invention comprises an upper bar 5 and a lower bar 6, the bars 5 and 6 being of channel construction, the open sides of the bars being disposed towards each other.

55 As clearly shown by Figure 6 of the drawings

the sides of the channel bars 5 and 6 are inclined inwardly, for purposes to be hereinafter more fully disclosed.

Connecting the ends of the bars 5 and 6, are 5 end bars 7, which have inwardly extended ends 8 that are formed with threaded openings that align with openings formed near the ends of the bars 5 and 6 for the reception of the screws 9, whereby the bars 5 and 6 are securely connected to the end bars of the frame.

The end bars 7 are formed with openings near 10 the ends thereof, the openings being elongated and of sizes to accommodate the ends of the heddle bars 10, the heddle bars 10 being of lengths to extend beyond the end bars 7 where they are 15 provided with openings, to receive the ends of the heddle bar retainers 11, that are carried by the end bars 7.

The heddle bar supporting rods are indicated by 20 the reference character 12, and each of these rods is formed with threaded ends 13, on which the clamping members 14 are mounted, the clamping members 14 being held in position by means of the heads 15 formed at the extremities of the rods 12.

25 These clamping members 14 are formed of sheet metal material and have sloping sides conforming to the shape of the bars 5 and 6, and are so constructed that they will closely fit within the channels of the bars 5 and 6, as clearly shown in Figure 6 of the drawings.

30 Cooperating with the inner clamping members 14 are outer clamping members 16, which are also formed of sheet material and shaped to conform to the shape of the bars 5 and 6, the outer clamping members being of widths to embrace portions of the outer surfaces of the channels.

35 Positioned on each threaded end of each heddle bar supporting rod 12, is a nut 17, which nut is adapted to be rotated to move the outer clamping member 16, associated therewith into clamping relation with the inner clamping member, to the end that when the nuts 17 have been properly positioned, the heddle bar supporting rods will be securely held in their positions of adjustment 40 longitudinally of the bars 5 and 6 of the frame.

45 Thus it will be seen that due to this construction, sectional heddles may be positioned on the frame, and the heddle bar supporting rods may be positioned so that the heddle bar supporting rods 12 will not interfere with the heddles, that is, the heddle bar supporting rods may be adjusted so that they are positioned at the side edges of the holders that fall adjacent to the rods 12.

55

Pivoted clips 18 are carried by the heddle bar supporting rods, and are formed with openings to receive the heddle bars 10, whereby the heddle bars may be readily and easily secured to the heddle frame.

5 Eye bolts indicated at 19 are secured to the heddle frame and provide means whereby the heddle frame may be supported.

Having thus described the invention, what is claimed is:

10 1. A heddle frame comprising upper and lower channel bars having their open sides disposed towards each other, heddle bar supports including rods disposed between the upper and lower bars, clamps at the ends of the rods, each clamp comprising an inner member and outer member, the inner member being disposed within the channel bars, the outer member cooperating with the inner member in clamping the channel bars, and means for securing the clamps to the channel bars.

15 2. A heddle frame comprising upper and lower channel bars, heddle bars forming part of the frame, heddle supporting rods, clamps at the ends of the heddle supporting rods, said clamps cooperating with the channel bars in securing the heddle supporting rods in their positions of adjustment longitudinally of the upper and lower channel bars, and means for removably securing the heddle bars to the supporting rods.

20 3. A heddle frame for supporting sectional heddles, comprising channel bars having their open sides disposed towards each other, the flanges of the channel bars being inwardly inclined,

25

heddle bars, heddle bar supports disposed between the channel bars, clamping members at the ends of the heddle bar supports and including plates conforming to the shape of the channel bars to clamp the channel bars, means for securing the clamps in their positions of adjustment to hold the heddle bar supporting rods in their positions of adjustment, and means for securing the heddle bars to the heddle bar supporting rods.

5 4. A heddle frame for supporting sectional heddles and comprising parallel bars, means for holding the parallel bars spaced apart at their ends, heddle bars, heddle bar supporting rods disposed between the parallel heddle bars holding the bars spaced apart intermediate the ends of the bars, 15 clamps at the ends of the heddle bar supporting rods, clamping the first mentioned parallel bars and securing the heddle bar supporting rods in their positions of adjustment, and means on the heddle bar supporting rods for securing a 20 heddle bar thereto.

5 5. A heddle frame for supporting sectional heddles, comprising parallel channel bars having their open sides disposed towards each other, heddle bars, heddle bar supports disposed between 25 the channel bars, clamps at the ends of the channel bar supports and fitted within the open sides of the channel bars, clamping the channel bars and adjustably securing the heddle bar supports to the channel bars, and clamps on the heddle 30 bar supports and adapted to clamp a heddle bar, securing the heddle bar to the heddle supports.

HOWARD O. CODDINGTON.
